UNITED STATES PATENT OFFICE.

ELMER R. CORWIN, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONE-EXCHANGE SYSTEM.

1,161,196.

Specification of Letters Patent. Patented Nov. 23, 1915.

Application filed July 15, 1912. Serial No. 709,407.

To all whom it may concern:

Be it known that I, ELMER R. CORWIN, citizen of the United States, residing at Chicago, in the county of Cook and State 5 of Illinois, have invented a certain new and useful Improvement in Telephone-Exchange Systems, of which the following is a full, clear, concise, and exact description, reference being had to the accompanying drawings, forming a part of this specification.

My invention relates to telephone exchange systems and has a number of objects and advantages in view.

In accordance with one feature of my 15 invention there are operator controlled electro-magnetic switches, less in number than the telephone lines, for connecting the answering ends of link connectors with calling lines.

20 In accordance with another feature of my invention there are employed electro-magnetic switches for connecting calling lines with calling line extensions extending toward called stations and which are herein 25 shown as being themselves called lines, though the invention is not to be limited to the direct and immediate connection of called lines with the link connectors.

In accordance with another feature of the 30 invention the operator controlled means which are employed for operating either or both kinds of switches are selected by calling line operated selector switches which also desirably associate calling line operated responsive devices, such as operators' 35 telephones, with calling lines.

I will explain my invention more fully by reference to the accompanying drawings showing the preferred embodiment 40 thereof and in which—

Figures 1 and 2, taken collectively and read with the conductors at the left and right of the figures and at the upper portion thereof in alinement, illustrate an exchange system as constructed in accordance 45 with the preferred embodiment of the invention to which embodiment the invention is not to be limited; and Fig. 3 is a detail view of some of the mechanism.

50 I have shown two telephone lines, the telephone stations illustrated happening to include telephone switch hooks 1, telephone receivers 2, transmitters 3, signal receivers 4,

and condensers 5, two stations 120 and 190 being illustrated with this apparatus. The 55 telephone lines, in the embodiment of the invention illustrated, each terminates at the same exchange (though it will become apparent that the lines do not need to terminate at the same exchange in order to practice my invention) in multiplied contacts 60 11 and multiplied contacts 12 constituting waiting contacts of a plurality of switches, each link connector including non-multiplied contacts 13¹ that are individual thereto and 65 which are in the form of switch wipers constituting parts of operator controlled switches for bringing the link connector terminals 13¹ into connection with calling line terminals 11, 12. The link connector terminals 13¹ at the left or calling line end of a link connector, are thus adapted for engagement with contacts 11, 12 of a calling line, and have companion link connector terminals 13² at the other end of the same link 70 connector, these latter terminals 13² being also controlled by the operator for the purpose of bringing them into connection with waiting contacts 11¹, 12¹ belonging to a called telephone line. Thus each telephone line has 75 its terminals 11, 12 which are employed when it is a calling line for extending it and which are not employed when it is a called line. Each telephone line also has its contacts 11¹, 12¹ that are employed when it is a called line and are not employed when it is a calling line. The contacts 11¹, 12¹ are 80 multiplied throughout the connecting or calling ends of the link connectors, being included in banks that are passed over by the 85 wipers 13². Thus the calling line end of each link connector (13¹) is accessible to calling line terminals 11, 12 and the called line end of each link connector (13²) is accessible to called line terminals 11¹, 12¹. 90 The mechanism by which the terminals 11, 12, 11¹ and 12¹ are engaged by their wipers will be later hereinafter set forth, and while I have shown the terminals 11¹ and 12¹ in Fig. 2 as pertaining to a telephone line, yet the invention is not to be limited to the nature of the line portions that are to be connected with calling lines by way of the contacts 11¹, 12¹.

In the drawings I have shown two operators' 105 positions A, B having operators'

telephones 13, 14 that constitute one form of responsive device which may be selected by calling stations, these responsive devices being operable by calling parties after their 5 selection though I do not limit myself to this form of responsive device. The operators' telephones 13 and 14 at positions A, B are connected respectively with conductors 15 and 16 that are individual thereto, these 10 conductors terminating in multiply related contacts 17, 18, 19 and 20 which constitute waiting or bank contacts for the wipers 22 and 23 of selector switches that are set into operation by calling lines for the purpose 15 of selecting operators' responsive devices that are free for selection.

As soon as a calling subscriber has removed his telephone from its switch hook the selecting mechanism individual to the 20 calling subscriber's line is set into operation. The circuit that causes the operation of the selecting mechanism when a calling subscriber initiates a connection is traceable from the grounded battery 35 through the 25 interrupter 34, the lower winding of the motor magnet 30, this lower winding constituting the motor winding, the bottom armature switch of relay 37 and its normal contact, the upper armature switch of relay 30 and its normal contact, both sides of the calling line, and the telephone transmitter and receiver connecting both sides of the calling line, to the grounded relay 40. The interrupter 34 causes the intermittent 35 energization of the motor winding of the magnet 30 whereby the armature of this motor magnet causes the pawl 32 to operate upon the ratchet wheel 21 whereby the wipers carried by this ratchet wheel are 40 brought into engagement with the set of waiting contacts pertaining to an idle operator. The wipers of the selecting devices are desirably normally out of contact with the waiting contacts and pass over these 45 contacts in the process of selecting a responsive device at an operator's position and which responsive device may be an operator's telephone. The responsive devices are free for selection when the circuits governing 50 the responsive devices are in their normal or idle conditions. Each responsive device has a governing circuit that may be traced from the ground 44, the switch of magnet 43, the selected waiting contact 27, 55 the wiper 24 engaging the same, the normal follow-up contact of the armature switch 47 of relay 37, the winding of relay 37, the contacts 41 when closed, to the grounded common battery 35. The armature switch 47 thereupon engages its alternate contact to establish a locking circuit for the relay 37 which may be traced from the now grounded armature switch 47 through the winding of relay 37, the now 60 engaged contacts 41, to the grounded bat-

tery 35. Circuit is consequently established for the magnet winding 43 which may be traced from the grounded terminal of relay 40, the winding of relay 40, one side of the calling line, the calling substation, the other 70 side of the calling line, the normal contact 38 and its armature switch, the alternate contact 48 and its armature switch, the wiper 23, the waiting contact 18 or 20 engaged by the wiper 23, the winding of the 75 device 43 to the grounded battery 35. When the magnet 43 is thus energized the ground 44 is removed from the multiplied selected contacts 27 so that when any wipers 24 engage contacts 27 from which the ground 80 has thus been removed the circuit for the magnet 37 will remain open so as to prevent the wipers of the moving switch from stopping, contacts 41 being closed when the wipers are in engagement with waiting 85 contacts and being open when out of engagement with said contacts. The wipers are stopped as a consequence of the opening of the motor winding circuit at 36 consequent upon the energization of the relay 37. 90 The selected operator, in response to the operation of her telephone receiver occasioned by the calling subscriber, ascertains the number of the line wanted.

At each operator's position there is a key 95 50 serving when depressed to establish a circuit which may be traced from the grounded battery 35 through the interrupter 51, the key contacts 52, the left hand armature switch of relay 53 and its normal contact, the motor magnet 54, to ground. As a consequence of the operation of the interrupter 51 the motor magnet 54 is intermittently energized so that its armature intermittently operates a pawl 55 to step the 100 ratchet wheel 56. This ratchet wheel 56 has an arm 57 fixed upon its shaft, this arm 57 carrying the wipers 13¹, and associate wipers later to be described, the wheel 56 stopping (by mechanism to be described) 105 when the wipers 13¹ are located above the waiting contacts 11, 12 of a calling line. When the button 50 is depressed, a notch 58 in its shank is engaged by the nose of the armature of a magnet 59 so that the button 50 is held depressed until it is released upon the energization of the magnet 59, the armature of said magnet being withdrawn from the notch 58 when said magnet is energized, whereby the button 50 is restored 110 and the contacts 52 are separated. When the button is restored the circuit for the magnet 59 is broken at 50 to restore the magnet to normal relation. The circuit for said magnet may be traced from the grounded 115 battery 35, the winding of the magnet, the contacts 60, the waiting contact 57¹, (multiplied as are the contacts 17, 18, etc.,) the wiper 58¹, the waiting contact 58², the wiper 58³, the right hand armature switch of relay 120 125 130

53 and its normal follow-up contact, the winding of said relay, the now closed contacts 61, to ground, the energization of magnet 59 occurring when the wiper 58³ (carried by arm 57) engages the waiting contact 58² in vertical alinement with the contacts 11, 12 of the calling line. When the magnet 53 is energized its armature switches engage their alternate contacts. 10 The right hand armature switch of the magnet 53 thereupon establishes a locking circuit for said magnet which may be traced from the grounded battery 35, the winding of said magnet, the contacts 61, to ground. 15 The left hand armature switch of magnet 53, when attracted, opens the circuit for the motor magnet 54 to stop the operation of the ratchet wheel 56. By the arrangement illustrated, ground is removed from contact 20 58³ when it has engaged the waiting contact 58² pertaining to the contacts 11, 12 of a calling line so that the magnets 59 at other operators' positions cannot be energized when their associate wipers 58³ engage their contacts 58². Each link connector is provided 25 with magnets 53 and 54. The motor magnets 54 associated with the different link connectors provided for each operator are partially governed by the left hand armature switches and the alternate contacts of preceding relays 53. When the relays 53 are energized circuit for the motor magnet 54 pertaining to the next link connector is partially closed at the alternate contact of 30 the left hand armature switch of the relay 53 of Fig. 1 and the right hand armature switch of relay 53 of Fig. 2 and the normal contact of this latter relay. Thus the link connectors are brought into service in succession. The operator next makes and breaks a circuit by the circuit interrupter 35, such circuit being traced from the grounded battery 35, the armature switch of magnet 63, and its contact, the winding of motor magnet 64, the wiper 25², the waiting contact 25¹, the wiper 25, the waiting contact 28 engaged by the wiper 25, to the key 62 and its grounded contact. The winding of motor magnet 64 is thereupon interrupted, the armature of said magnet thereupon causing pawl 65 to turn the ratchet wheel 66. The ratchet wheel 66 carries an arm 67 upon which the wipers 13² are mounted. The operator knows how far to step 40 the wipers 13² and ceases the operation of the key 62 when the wipers 13² are brought over the contacts 11¹, 12¹. When a wiper 13² is over the contact 11¹ a test circuit is established which is either opened or closed at 45 the substation according to the busy or idle condition of the called line.

Assuming that the line desired is free, the operator includes a source of ringing current 49 in circuit with the called line by 50 engaging the ringing key contacts 68. After

the desired subscriber has been called the operator manipulates the key 69 to establish a circuit through the wiper depressing magnet 70, the circuit established being traceable from the grounded contact of key 69, 70 the waiting contact 29, the wiper 26 then engaging the same, the waiting contact 26¹, the wiper 26² then engaging the same, the normal follow-up contact of the relay 70, the winding of said relay, to the grounded 75 battery 35. As a consequence, the relay 70 is energized to draw down its upper armature that is mounted upon the arm 57 to depress the wipers carried by said arm and bring the wipers 13¹ into engagement with 80 the talking contacts 11, 12 of the calling line. When the relay or magnet 70 is energized, the mechanical connection 71 raises the pawl 55 to permit the ratchet wheel 56 to restore to normal when the relay 70 is 85 later deenergized, the relay 70 when energized holding the wiper supporting arm 57 from rotation, this arm being fixed with respect to the wheel 56, the arrangement shown in Fig. 3 being adaptable. 90

In Fig. 3 the core of the magnet 70 is extended so as to afford a non-rotating circular pole co-axial with the toothed wheel 56. The arm 57 is connected with the disk 56 at its center so as to rotate with the disk 95 while also movable toward and from the plane of the disk. The armature for the magnet 70 is carried upon the arm 57 and overlies the circular extension of the core of the magnet 70 so that the arm 57 may be 100 attracted for the purpose of bodily moving the wipers, when rotated to position, in a direction transverse to their plane of rotation.

The wipers 13¹ and 73 constitute calling 105 line terminals of a link connector which may be provided at its other end with a suitable connecting apparatus which may be located at the same or different exchange and which is suited to the plan of the system. I have 110 equipped the other end of this link connector with operator controlled electro-magnetic mechanism for further extending the link connector, in this case such operator controlled electro-magnetic mechanism serving 115 to effect the connection of the link connector with a called line to which function the link connector, however, is not to be limited. The mechanism illustrated in Fig. 2 for connecting the link connector with a called line 120 has mechanical structure illustrated in Fig. 3, the magnet 64 serving to step the ratchet wheel 66 around while the magnet 63 serves, when energized, to lift a pawl 65 and press the wipers 13² upon the waiting contacts 11¹, 12¹, the elements 64 and 63 being 125 similar in this respect to the elements 54 and 70 and it will not therefore be necessary to describe more in detail the mechanical arrangement of the elements 63, 64 and their 130

associate parts. The motor magnet 64 is intermittently energized as a result of the operator's key 62 which serves to make and break the circuit of the magnet 64 a sufficient number of times to bring the wipers 13² over the waiting contacts 11¹, 12¹, preparatory to the depression of these wipers by the magnet 63 if the desired line is found to be idle. If the desired line is busy a noisy test circuit 10 is established which is traceable from the grounded interrupter test magnet 74, the right hand operator's primary coil, the test contacts 75 of an operator's test key, the waiting contact 57, the wiper 58, the waiting 15 contact 13³ of the calling line, the wiper 13⁴ engaging said contact 13³, the upper wiper 13², the waiting contact 11¹ of the desired line, one side of the desired line and its substation, the other side of the desired line, 20 the upper armature switch of relay 39 belonging to the desired line, the alternate contact of such armature switch, the armature switch of relay 40 individual to the desired line and its contact, the contact 72 of 25 the desired line, the wiper 73, the armature switch of relay 70 and its alternate contact, to the grounded battery 35 by way of the winding of relay 70. If the desired line is free, the operator includes the ringing 30 generator 49 in circuit with the called line by engaging the ringing contact 68, the ringing circuit being traceable from the grounded generator 49 through the closed ringing contact 68, the waiting contact 57, 35 the wiper 58, the waiting contact 13³, the wiper 13⁴, the upper wiper 13², the contact 11¹ of the called line, one side of the called line, the switch hook 1 of the called line, to the grounded signal bell 4 at the called 40 station. The operator does not manipulate the key 69 until the testing and ringing operations have been effected and consequently neither of the magnets 70 and 63 is operated until the key 69 is operated and both of 45 these magnets are operated together upon the manipulation of the key 69, the magnet 70 being operated directly by the key 69 while the magnet 63 has circuit closed there-through by the armature switch of magnet 50 70 when such switch is moved upon the energization of such magnet 70, the circuit for the magnet 63 being traceable from the grounded battery 35, the winding of magnet 70, its armature switch and the alternate 55 contact thereof, the wiper 73, the waiting contact 72, the armature switch of magnet 40 of the calling line, the calling line talking contact 12, the lower wiper 13¹ then engaging the same, the magnet 63, to ground. 60 When the key 69 is depressed the operator's telephone and the operator selector associating the same with the calling line are disconnected from the calling line as a consequence of the energization of the magnet 65 70, the key 69 being depressed for this purpose

whether the calling line has secured connection with the desired line or not. When the magnet 70 is energized its armature switch engages its alternate contact to establish a locking circuit through the magnet which may be traced from the grounded battery 35 through the winding of the magnet 70, its armature switch and the alternate contact thereof, the armature switch of relay 40, the winding of relay 39, to ground. Another circuit is established which includes the magnet 40, the calling subscriber's line, the upper armature switch of relay 39 and its alternate contact, the armature switch of relay 40, the waiting contact 72, the wiper 73 now pressed down into engagement with contact 72 by the magnet 70, the winding of magnet 70 and its alternate contact, and the grounded battery 35. The calling subscriber thus has control of the magnet 40 when the operator responsive device selecting mechanism previously set into operation by the calling subscriber has been operated to disconnect the calling subscriber's line from the selected conductors leading to the selected operator. The magnet 70 will now remain energized as long as the calling subscriber's telephone is free of its switch hook, the magnet 40 being deenergized when the calling subscriber restores his telephone upon its switch hook, whereupon magnet 70 is deenergized to open its circuit and release the arm 57 whereupon the wheel 56 is permitted to restore to normal (the pawl 55 having previously been disengaged) the wheel 56 in restoring to normal carrying with it the wipers fixed upon its shaft. When the magnet 70 is deenergized it opens the circuit of magnet 63 so that the wipers 13² previously associated with the desired line are restored to normal. If the called subscriber has responded the magnet 40 will not be deenergized until the receivers at both stations are restored so that the wipers carried by the wheels 56 and 66 will not be restored until both subscribers replace their telephones upon their switch hooks. 105

The wipers carried by the wheel 56 having been depressed by the magnet 70, which operation is followed by the energization of the relay 39, the selector automatically set into operation by the calling subscriber for selecting the operator's telephone or other responsive device of an idle operator, is moved one step to a position in which the contacts 41 are separated and in which the conductors extending to the idle operator are disconnected from the wipers that previously had associated them with the calling line. This result is due to the separation of the upper armature switch of calling subscriber's relay 39 from its normal contact whereby the circuit through the motor magnet 30 is opened, a circuit at the same time being established through the upper winding 115 120 125 130

of the motor magnet that is traceable from the lower grounded armature switch of relay 39, said upper winding of the motor magnet 30, the contacts 41, to the grounded battery 35. The magnet 30 now operates to pull the ratchet wheel 21 to a position in which the contacts 41 are separated and in which the wipers carried by the wheel 21 are removed from engagement with the waiting contacts that were engaged thereby for the purpose of connecting an idle operator with a calling subscriber. The separation of the contacts 41 causes the relay 37 to be deenergized so as to dissociate the wipers carried by the wheel 21 from the calling line, these wipers now having been stepped into dead positions between waiting contacts.

It will be unnecessary to describe how the mechanism for selecting idle operators is prevented from being operated by responding called lines.

The keys or buttons 50 taken with their magnets 59 constitute testing or indicating devices, the keys, when released by the attraction of the armatures of magnets 59, serving to inform the operators when the calling line ends of the link connectors have become connected with calling lines. The magnets 59 and their associate keys 50 are individual to the operators as are also the contacts 60. The contacts 52 however are multiplied through the various operators' positions so that any operator may employ any idle switching mechanism for connecting a calling line with an idle link connector. As the link connecting mechanism would probably not be visible, the keys 50 serve, when released, to inform the operator when a link connector has been connected with a calling line.

In the specification and claims I have used the term "link connector" meaning thereby sections of telephone circuits each adapted for interchangeable connection with calling lines and with called lines, the operator being provided with means whereby a link connector may be brought into connection with any of several calling lines.

While I have herein shown and particularly described the preferred embodiment of my invention I do not wish to be limited to the precise details of construction and circuit arrangement shown as changes may readily be made without departing from the spirit thereof, but

Having thus described my invention, I claim as new and desire to secure by Letters Patent the following:—

1. A telephone exchange system including telephone lines extending to an exchange; extensions for calling telephone lines; a plurality of link connectors inclusive of operator controlled motor means for connecting the calling and called line ends thereof with calling lines and further extensions thereof;

and calling line operated selector switches for selecting unemployed link connectors, the connecting equipment for the link connectors adapting them to their line joining function independently of the selector switches.

2. A telephone exchange system including telephone lines extending to an exchange; extensions for calling telephone lines; a plurality of link connectors inclusive of operator controlled motor means for connecting the called line ends thereof with further extensions of calling lines; and calling line operated selector switches for selecting unemployed link connectors, the connecting equipment for the link connectors adapting them to their line joining function independently of the selector switches.

3. A telephone exchange system including telephone lines extending to an exchange; extensions for calling telephone lines; a plurality of link connectors inclusive of operator controlled motor means for connecting the calling and called line ends thereof with calling lines and further extensions thereof; and calling line operated selector switches for selecting link connectors, the connecting equipment for the link connectors adapting them to their line joining function independently of the selector switches.

4. A telephone exchange system including telephone lines extending to an exchange; extensions for calling telephone lines; a plurality of link connectors inclusive of operator controlled motor means for connecting the called line ends thereof with further extensions of calling lines; and calling line operated selector switches for selecting link connectors, the connecting equipment for the link connectors adapting them to their line joining function independently of the selector switches.

5. A telephone exchange system including telephone lines extending to an exchange; extensions for calling telephone lines; a plurality of link connectors inclusive of operator controlled motor means for connecting the calling and called line ends thereof with calling lines and further extensions thereof; operators' means for controlling the motor means; and calling line operated selector switches initially operated by calling lines when initiating calls and employed in the selection of operators' means, the connecting equipment for the link connectors adapting them to their line joining function independently of said selector switches.

6. A telephone exchange system including telephone lines extending to an exchange; extensions for calling telephone lines; a plurality of link connectors inclusive of operator controlled motor means for connecting the calling and called line ends thereof with calling lines and further extensions thereof; operators' means for controlling the motor

means; and calling line operated selector switches for selecting operators' means, the connecting equipment for the link connectors adapting them to their line joining function independently of said selector switches.

7. A telephone exchange system including telephone lines extending to exchange operators' positions; link connectors for joining telephone lines; motor means, less in number than the lines, at the exchange for connecting called line ends of link connectors with lines to be joined with calling telephone lines; operator controlled means at the operators' positions for governing the operation of the aforesaid means; selector switches operable by calling lines for selecting operator controlled means, the connecting equipment for the link connectors adapting them to their line joining function independently of the selector switches; and operators' telephones associated with the operator controlled means and in selectable relation to the selector switches that are provided with means for relating selected telephones to calling lines.

8. A telephone exchange system including telephone lines extending to exchange operators' positions; link connectors for joining telephone lines; motor means, less in number than the lines, at the exchange for connecting called line ends of link connectors with lines to be joined with calling telephone lines; operator controlled means at the operators' positions for governing the operation of the aforesaid means; selector switches operable by calling lines for selecting operator controlled means, the connecting equipment for the link connectors adapting them to their line joining function independently of the selector switches; and calling line operated responsive devices associated with the operator controlled means and in selectable relation to the selector switches that are provided with means for relating selected responsive devices to calling lines.

9. A telephone exchange system including telephone lines extending to exchange operators' positions; link connectors for joining telephone lines; motor means, less in number than the lines, at the exchange for connecting calling line ends of link connectors with calling lines; motor means, less in number than the lines, at the exchange for connecting called line ends of link connectors with lines to be joined with calling telephone lines; operator controlled means at the operators' positions for governing the operation of the aforesaid means; selector switches operable by calling lines for selecting operator controlled means, the connecting equipment for the link connectors adapting them to their line joining function independently of the selector switches; and operators' telephones associated with the operator con-

trolled means and in selectable relation to the selector switches that are provided with means for relating selected telephones to calling lines.

10. A telephone exchange system including telephone lines extending to exchange operators' positions; link connectors for joining telephone lines; motor means, less in number than the lines, at the exchange for connecting calling line ends of link connectors with calling lines; operator controlled means at the operators' positions for governing the operation of the aforesaid means; selector switches operable by calling lines for selecting operator controlled means, the connecting equipment for the link connectors adapting them to their line joining function independently of the selector switches; and calling line operated responsive devices associated with the operator controlled means and in selectable relation to the selector switches that are provided with means for relating selected responsive devices to calling lines.

11. A telephone exchange system including telephone lines extending to an exchange, there being contacts pertaining to calling lines; extensions for extending calling lines, there being contacts belonging to these extensions for including them in circuit with calling lines; a plurality of link connectors each having contacts at the calling and called line ends thereof; motor means for effecting engagement between the contacts at the calling line ends of link connectors and contacts pertaining to calling lines and for effecting engagement between the contacts at the called line ends of link connectors and contacts belonging to calling line extensions, the motor means associated with the calling line ends of the link connectors and also the motor means associated with the called line ends of the link connectors being less in number than the telephone lines; operator controlled means at the operators' positions for governing the operation of the motor means; and selector switches for selecting operator controlled means.

12. A telephone exchange system including telephone lines extending to an exchange, there being contacts pertaining to calling lines; extensions for extending calling lines, there being contacts belonging to these extensions for including them in circuit with calling lines; a plurality of link connectors each having contacts at the calling and called line ends thereof; motor means for effecting engagement between the contacts at the calling line ends of link connectors and contacts pertaining to calling

lines and for effecting engagement between the contacts at the called line ends of link connectors and contacts belonging to calling line extensions, the motor means associated 5 with the calling line ends of the link connectors and also the motor means associated with the called line ends of the link connectors being less in number than the telephone lines; operator controlled means at 10 the operators' positions for governing the operation of the motor means; and calling line operated selector switches for selecting operator controlled means.

13. A telephone exchange system including telephone lines extending to an exchange, there being contacts pertaining to calling lines; extensions for extending calling lines, there being contacts belonging to these extensions for including them in circuit with calling lines; a plurality of link connectors each having contacts at the calling and called line ends thereof; motor means for effecting engagement between the contacts at the calling line ends of link connectors and contacts pertaining to calling lines and for effecting engagement between the contacts at the called line ends of link connectors and contacts belonging to calling line extensions, the motor means associated with the calling line ends of the link connectors and also the motor means associated with the called line ends of the link connectors being less in number than the telephone lines; operator controlled means at the operators' positions for governing the operation of the motor means; and selector switches for selecting operator controlled means and link connectors.

40 14. A telephone exchange system including telephone lines extending to an exchange, there being contacts pertaining to calling lines; extensions for extending calling lines; a plurality of link connectors each having contacts at the calling and called line ends
45 thereof for connection with contacts pertaining to calling lines and their extensions; motor means, less in number than the telephone lines, for effecting engagement between contacts at the calling line ends of
50 link connectors and contacts pertaining to calling lines; operator controlled means at the operators' positions for governing the operation of the motor means; and selector switches for selecting operator controlled
55 means and link connectors.

15. A telephone exchange system including telephone lines extending to an exchange, there being contacts pertaining to calling lines; extensions for extending calling lines, there being contacts belonging to these extensions for including them in circuit with calling lines; a plurality of link connectors each having contacts at the calling and called line ends thereof; motor means for effecting engagement between the contacts at the call-

ing line ends of link connectors and contacts pertaining to calling lines and for effecting engagement between the contacts at the called line ends of link connectors and contacts belonging to calling line extensions, 70 the motor means associated with the calling line ends of the link connectors and also the motor means associated with the called line ends of the link connectors being less in number than the telephone lines; operator controlled means at the operators' positions for governing the operation of the motor means; and calling line operated selector switches for selecting operator controlled means and link connectors. 75 80

16. A telephone exchange system including telephone lines extending to an exchange, there being contacts pertaining to calling lines; extensions for extending calling lines; a plurality of link connectors each having contacts at the calling and called line ends thereof for connection with contacts pertaining to calling lines and their extensions; motor means, less in number than the telephone lines, for effecting engagement between contacts at the calling line ends of link connectors and contacts pertaining to calling lines; operator controlled means at the operators' positions for governing the operation of the motor means; and calling line operated selector switches for selecting operator controlled means and link connectors.

17. A telephone exchange system including telephone lines extending to an exchange, there being contacts pertaining to calling lines; extensions for extending calling lines, there being contacts belonging to these extensions for including them in circuit with calling lines; a plurality of link connectors each having contacts at the calling and called line ends thereof; motor means for effecting engagement between the contacts at the calling line ends of link connectors and contacts pertaining to calling lines and for effecting engagement between the contacts at the called line ends of link connectors and contacts belonging to calling line extensions, the motor means associated with the calling line ends of the link connectors and also the motor means associated with the called line ends of the link connectors being less in number than the telephone lines; operator controlled means at the operators' positions for governing the operation of the motor means; and calling line operated selector switches for selecting link connectors.

18. A telephone exchange system including telephone lines extending to an exchange, there being contacts pertaining to calling lines; extensions for extending calling lines; a plurality of link connectors each having contacts at the calling and called line ends thereof for connection with contacts per- 130 125

taining to calling lines and their extensions; motor means, less in number than the telephone lines, for effecting engagement between contacts at the calling line ends of link connectors and contacts pertaining to calling lines; operator controlled means at the operators' positions for governing the operation of the motor means; and calling

line operated selector switches for selecting link connectors.

In witness whereof, I hereunto subscribe my name this third day of July A. D., 1912.

ELMER R. CORWIN.
